Application March 12, 1954, Serial No. 29,492

Term of patent 3½ years

(Cl. D25—1)

FIG. 1

FIG. 2

To all whom it may concern:

Be it known that we, Sidney Mischnon and William B. Lichtner, citizens of the United States of America and residents of the city of New York, in the county of Queens and State of New York, have invented a new, original, and ornamental Design for a Combined Drawing Board and Crayon Dispenser or Similar Article, of which the following is a specification, reference being had to the accompanying drawing, forming a part thereof.

Fig. 1 is a perspective view of a combined drawing board and crayon dispenser or similar article, showing our new design; and

Fig. 2 is a cross-sectional view thereof taken on line 2—2 in FIG. 1.

Portions of the drawing figures are lined to indicate color contrast.

The dominant features of my new design are shown in solid lines.

We claim:

The ornamental design for a combined drawing board and crayon dispenser or similar article, substantially as shown and described.
